UNITED STATES PATENT OFFICE.

JAMES B. BAYNES, OF BUFFALO, NEW YORK.

VEHICLE-AXLE.

SPECIFICATION forming part of Letters Patent No. 763,839, dated June 28, 1904.

Application filed March 17, 1904. Serial No. 198,567. (No model.)

To all whom it may concern:

Be it known that I, JAMES B. BAYNES, a citizen of the United States, and a resident of Buffalo, in the county of Erie and State of New York, have invented a new and useful Improvement in Vehicle-Axes, of which the following is a specification.

This invention relates to that class of duplex vehicle-axes which are composed of two separate members having their end portions diverging from each axle spindle or arm and having their main portions extending lengthwise side by side, the two members being united at their ends adjacent to each axle arm or spindle and usually connected by braces or stays at one or more intermediate points.

The object of this invention is to produce an axle of this general character which is strong, rigid, and comparatively light and also attractive in appearance.

In the accompanying drawings, Figure 1 is a longitudinal elevation of this improved axle. Fig. 2 is a top plan view thereof. Fig. 3 is a fragmentary partly-sectional elevation of the axle on an enlarged scale. Figs. 4 and 5 are vertical cross-sections in lines 4-4 and 5-5, Fig. 3, on an enlarged scale. Figs. 6 and 7 are cross-sections in lines 6-6 and 7-7, Fig. 3, on an enlarged scale. Fig. 8 is a sectional end elevation in line 8-8, Fig. 3, on an enlarged scale. Fig. 9 is a similar view showing a slightly-modified construction. Fig. 10 is a perspective view of the block or nut with which the vertical fastening-bolt engages. Fig. 11 is a vertical cross-section showing the spring clipped to the axle.

Like letters of reference refer to like parts in the several figures.

40 A represents the main or longitudinal portions of the two members of the axle, A' the depending and downwardly-converging end portions thereof, and B the axle arms or spindles. Each member of the axle is composed, preferably, of a body or core C, of suitable metal, and two wooden beds, fillings, or facings D, secured to the body C on opposite sides thereof by clips d or other suitable fastenings. As shown in Fig. 6, the metallic body 45 or core C has preferably a cross-sectional

form approaching that of an I-beam, but having the edges of its flanges e connected with its web c' by concave faces c". The wooden beds D are shaped to fit against the flat sides and the concave end faces of the web, and the 55 ends of the flanges e of the core are mounted to follow the convex curvature of the outer faces of the wooden beds. This form of cross-section is very strong and rigid for its weight and permits the metallic body and wooden beds 60 to be easily produced of the proper shape to form a close fit of the respective parts against each other.

The two members of the duplex axle, which are arranged side by side with reference to 65 the longitudinal direction of the axle, are so shaped that they approach each other at the middle and ends and are spaced apart between these points, corresponding points in the two members being located in the same horizontal 70 plane. The two members of the duplex axle have their middle portions a secured together and form on each side of the middle portions an open loop E, Fig. 2, so that each duplex axle presents the form of two elongated loops 75 and a central constricted portion, in which latter the two members of the axle are united. This looped form renders the axle very stiff and rigid in all directions and furnishes at 80 the middle a convenient seat e for an elliptic or other spring F. An oblong form of loop is preferred; but other forms may be used. When an elliptic spring is used, the seat e on the constricted middle portion of the axle is 85 preferably made concave, as shown in Figs. 1 and 3. The two members of the axle may be secured together at the middle by transverse rivets g, Fig. 5, or by clips g', Fig. 11, which also secure the spring to the axle. The spring may, however, be secured to the middle portion of the axle by upright bolts H, Fig. 4, arranged between the two members of the axle and engaging with their lower ends in blocks or elongated nuts I, which are seated between the lower portions of the two members of the 95 axle and are each provided with a threaded opening i, Fig. 10, for the reception of the bolt. These blocks or nuts also serve as spacing-blocks for the two members of the axle. The two members of the axle are preferably 100

connected in the wide part of each loop by a transverse stay or brace *k*.

Each axle-spindle or arm *B* is secured in an eye *L*, which is provided with an upwardly-extending bifurcated or V-shaped shank *l*, so shaped as to connect with the depending and downwardly-converging end portions of the metallic cores of the two members of the axle. This bifurcated shank may be secured to the metallic cores in any suitable manner. For instance, as shown in Fig. 8, its branches or arms may be shaped so as to lie against the inner side of each core and be riveted to the core, or, as shown in Fig. 9, it may be arranged so that its branches form continuations of the metallic cores and be welded to the same.

I claim as my invention—

1. A duplex vehicle-axle comprising two separate and similar members, arranged side by side with reference to the longitudinal direction of the axle and having corresponding points in the two members located in the same horizontal plane, said two members having their middle portions and end portions arranged in proximity and secured together, while the intermediate portions of the members between the middle and end portions are spaced apart, substantially as set forth.
2. A duplex vehicle-axle which consists of two separate members secured together at the middle and at both ends adjacent to the spindles and forming elongated loops between the middle and the axle-spindles, substantially as set forth.
3. A duplex vehicle-axle which consists of

two separate members arranged side by side with reference to the longitudinal direction of the axle and secured together at the middle and at both ends adjacent to the spindles and forming elongated loops between the middle and the axle-spindles, the middle portions of both members forming a seat for a spring, substantially as set forth.

4. The combination of a duplex vehicle-axle comprising two separate members which are secured together at the middle and at both ends and arranged at a distance from each other intermediate the said points of connection, a spring arranged upon the middle portions of said members, a space-block arranged between the middle portions of the axle, and a vertical fastening-bolt arranged between said members and engaging in said space-block, substantially as set forth.

5. A duplex vehicle-axle comprising two separate and similar members arranged side by side with reference to the longitudinal direction of the axle, said members being arranged in proximity to each other at the middle and at both ends of the axle and spaced apart between the middle and ends, forming on each side of the middle an elongated open loop, substantially as set forth.

Witness my hand this 8th day of March, 1904.

JAS. B. BAYNES.
